UNITED STATES PATENT OFFICE.

JOSEPH S. DUNCAN, OF CHICAGO, ILLINOIS, ASSIGNOR, BY MESNE ASSIGNMENTS, TO ADDRESSOGRAPH COMPANY, OF CHICAGO, ILLINOIS, A CORPORATION OF DELAWARE.

PRINTING MACHINE.

Application filed May 10, 1924. Serial No. 712,270.

This invention is particularly adapted to be embodied in a printing machine of the type in which a plurality of printing devices are presented to a platen, one by one, and in which means are provided for feeding a blank, a sheet of paper, or the like, to a printing position.

To facilitate the disclosure of my invention, I will first briefly describe the work 10 which a machine embodying one form of my invention is adapted to do.

I have embodied the invention in a printing machine which is primarily intended to be employed in the printing of tax lists. 15 This work, the printing of tax lists, may be divided roughly into two classes. The first class may be said to include all tax lists in which the descriptions of the various parcels of land, together with the names of the 20 holders of title thereto, are printed in a single column upon a blank of comparatively large dimensions. The second class of tax lists would then be the lists which have the descriptions of the various parcels 25 of land printed in one column of a blank and the names of the holders of title printed in another column of the blank. While I make particular reference to the tax lists pertaining to real property, it is apparent 30 that the tax lists pertaining to personal property will fall within these classes and that a machine adapted to print tax lists relating to real property would also be adapted 35 to print tax lists relating to personal property.

A printing device adapted to be employed in a printing machine of the character described may carry the description of a parcel of land and also the name and address of 40 the holder of title thereto, but, in many instances, the fee to several adjacent parcels of land is held by an individual and the data must be spread upon several printing devices. If the tax list is to occupy a single 45 column on the blank, it is readily understood that each printing device will then be presented to the platen in its proper turn and that a single impression will be made thereof. But if the tax list is to occupy a 50 plurality of columns on the blank, a printing device carrying both the description of a parcel of land and the name of the holder of title thereto must be presented to the platen a plurality of times so that the impression 55 of the name of the holder of title

may be placed in one column and so that the impression of the description of the land may be placed in another column, it being understood that my invention contemplates printing devices of standard or convenient 60 dimensions.

In the prior art, the term "consecutive printing" has been applied to the act of successively feeding the printing devices to a platen by mechanism which is adapted to 65 present each printing device to the platen a single time. Also, the term "duplicating" has been applied to the act of presenting a printing device to a platen a plurality of times. I wish to employ the term "divided 70 printing" to distinguish from the terms "consecutive printing" and "duplicating", the term "divided printing" being employed to describe the act of making an impression of a portion of a printing device in one column of a blank and another impression of a different portion of the printing device in another column of the blank. Of course, divided printing contemplates the use of 75 "duplicating" mechanism as in divided 80 printing it is necessary to present the printing plate to the platen a plurality of times.

In practice, it is customary to print several tax lists, each of which deals with the same land or property. Some of the lists 85 are "single column" lists, the remainder being "double column" lists. The reason for this practice is not material to this disclosure and therefore will not be given, but the practice makes necessary the provision of 90 some means for identifying each entry so that one may refer from one of the lists to another of the lists with little trouble. Usually each entry or item is identified by 95 the number of the volume in which it is contained and by a number which has been assigned to that particular entry or item. For instance, an entry given the holder of title either of a single parcel of land or of several adjacent parcels of land would be 100 given a volume number and one of a series of consecutive numbers. It follows then that where the descriptions of various parcels of land, held by an individual are spread over several printing plates, the printing 105 machine, if it is to correctly number the entry, must be adapted to print only one volume number and only one item number for each entry whether the entry is carried 110 by a single printing device or whether it is

spread over several printing devices. My improved addressing machine preferably embodies means for properly numbering such entries of the tax lists.

5 The object of the invention is broadly to provide an improved printing machine of the character described capable of doing the work described above, or of doing work of a similar nature.

10 A further object of the invention is to provide a printing machine of the character described adapted to make impressions in two columns of a blank, the columns being spaced from each other a distance which

15 prohibits simultaneous printing of the impressions.

A further object of the invention is to provide an improved printing machine of the character described having mechanism 20 for printing an identifying symbol or a number for a single impression or for a group of impressions, the mechanism for printing the symbol or number being controlled by the printing devices so that the entries may be passed through the printing machine in any order.

A further object of the invention is to provide an improved printing machine having a numbering mechanism and having improved means for actuating the accumulating mechanism thereof.

30 A further object of the invention is to provide an improved printing machine of the character described which has means for shifting the blank back and forth so that impressions may be made in each of two columns on the blank.

40 A further object of the invention is to provide an improved printing machine of the character described having improved means for feeding the blank so that separate impressions can be made in a plurality of columns on the blank.

45 A still further object of the invention is to provide a printing machine of the character described which has improved means whereby the machine may be set to either present each printing device to the platen a single time or to present each printing device to the platen a plurality of times, and which has means correlated to the first mentioned means and adapted to assign proper identifying symbols or numbers to the various entries.

55 Other objects of my invention will become apparent as the detail description progresses, reference being had to the accompanying drawings, wherein.

60 Fig. 1 is a plan view of an addressing machine embodying the novel features of my invention.

Fig. 2 is a side elevation of the addressing machine, the view being taken from the right of Fig. 1.

65 Fig. 3 is a side elevation of the addressing

machine looking from the left of Fig. 1, several parts of the machine being broken away to illustrate certain details of construction.

Fig. 4 is a fragmentary elevation of certain operating mechanism of the addressing machine, the view being an enlargement of a portion of Fig. 2.

Fig. 5 is another view of the mechanism shown in Fig. 4, the mechanism being shown 75 in a changed position.

Fig. 6 is a fragmentary side elevation of duplicating mechanism which forms a part of my improved addressing machine.

Fig. 10 is a section taken on line 10—10 of Fig. 2.

Fig. 11 is a side elevation partly in section of the blank or paper holder of the addressing machine.

Fig. 12 is a section taken on line 12—12 of Fig. 4.

Fig. 13 is a bottom plan elevation of platen mechanism forming a part of my improved addressing machine.

Fig. 14 is a section taken on line 14—14 of Fig. 2.

Fig. 15 is a plan of some of the parts shown in Fig. 8, the parts being shown in changed positions.

Figs. 16, 17, 18 and 19 illustrate various positions and adjustments of a mechanism for controlling certain operations of the printing machine, the printing machine being set to present each printing device to the 105 platen a plurality of times.

Figs. 20, 21, 22 and 23 illustrate various positions and adjustments of the mechanism shown in Figs. 16 to 19 inclusive, the printing machine being set or adjusted to present each printing device to the platen a single time.

Fig. 24 is a section taken on line 24—24 of Fig. 16.

Fig. 25 illustrates the manner in which 115 certain parts of the platen mechanism are adjusted when each printing device is to be presented to the platen a single time.

Fig. 26 is a view of one of the printing devices employed in my improved addressing 120 machine.

Fig. 27 is a fragmentary view of a blank illustrating the manner in which the printing is arranged when the machine is set for "consecutive" printing, and

Fig. 28 is a fragmentary view of a blank showing the manner in which the printing is arranged when the machine is set for "duplicating" and "divided" printing.

Referring for the present to Figs. 1, 2 and 130

3, my improved addressing machine comprises a frame which is designated generally by the reference character 30. The frame 30 is provided with a work-table 31 upon the rear end of which I prefer to mount a motor 32 adapted to drive a pulley 33 by means of a belt 34. The pulley 33 is rotatably journaled upon a shaft 34^a which is in turn rotatably journaled in the frame 30, the shaft being disposed beneath the work-table 31 and being arranged transversely thereof. The pulley 33 forms part of a clutch which resembles clutches of the type generally employed in machines of this character. These clutches automatically disconnect the mechanism of a machine from its driving means when a cycle of operations has been completed unless other means are positioned to hold the several members of the clutch in driving engagement. In this instance, the driving and driven members of the clutch are brought into driving engagement by means of a foot treadle (not shown) which trips a pivoted lever 35 through the medium of a rod 36 pivotally secured to the free end of the lever. When the lever 35 is tripped, the driving and driven members of the clutch engage each other and permit the machine to be driven through a cycle of operations whereupon the driving and driven elements are automatically disengaged unless other means, hereinafter described, are positioned to keep the members in driving engagement. The driven member of the clutch is indicated diagrammatically at 37 and is adapted to reciprocate a pitman 38 which is pivotally secured to the driven member by means of a crank pin 39. The clutch is so designed that one revolution of the driven member 37 is equivalent to a complete cycle of operations of the machine. This permits the pitman 38 to be secured directly, by a pin 40, to an operating member 41 which is adapted to oscillate about the axis of a pin 42 journaled in the frame 30. The operating member 41 has a cam slot 43 in which an anti-friction roller 44 is adapted to ride, the anti-friction roller 44 being carried by the extension 45 of a platen arm 46 which is pivotally mounted upon an oscillating shaft 47 journaled in the frame 30. The shaft 47 is disposed beneath the work-table 31 but the platen arm 46 extends upwardly through an aperture in the work-table and carries at its free end certain parts of a platen mechanism which is designated, in its entirety, by the reference character 48.

The platen mechanism.

60 The platen mechanism 48 preferably comprises a platen roller 49 journaled in bifurcations 50 of a platen lever 51 which is pivotally secured, by means of a pin 52, to a downwardly extending arm 53, of a sleeve 54 (Figs. 2, 4, 10 and 13). The sleeve 54 is pivotally mounted upon the pin 55 carried by the platen arm 46 and is provided with a rearwardly extending arm 56 which is connected by means of a link 57 to a lever 58 pivotally mounted on the shaft 47 (Figs. 2, 4, 5 and 10). The lever 58 is adapted to be angularly displaced about the axis of the shaft 47 by a block 59 which is also pivoted upon the shaft 47. The block 59 carries lugs 60 and 61 designed to engage the lever 58 alternately and to displace the lever about the axis of the shaft 47, the lugs being so arranged as to permit the lever 58 to remain at rest for a brief period of time between alternate engagements thereof by the lugs. 75 The block 59 is also provided with a downwardly extending arm 62 which is pivotally connected to one end of a link 63 by a pin 64, the other end of the link being pivotally connected to the operating member 41 by a pin 65. The purpose of this construction will presently appear.

As best shown in Figs. 4 and 12, the bifurcated end of the platen lever 51 is slidably journaled upon a cam plate 66, each of the bifurcations 50 being provided, for this purpose, with a pin 67 and a roller 68. The cam plate 66 is itself slidably journaled upon the platen arm 46, the cam plate being secured to the platen arm by a plurality of 90 shouldered screws 69 which permit the cam plate to be moved into a plurality of positions by means including links 70 and 70^a. The link 70 has one of its ends pivotally secured to the cam plate 66 and the other of 100 its ends pivotally secured to a downwardly extending lever 71 of a frame 72 which comprises a bar 73 formed integrally with two other downwardly extending levers 74 and 75 (Fig. 10). The frame 72 is pivotally 105 mounted upon the pin 55, the levers 74 and 75 being provided with suitable apertures for this purpose. The link 70^a connects the lower end of the lever 74 with the cam plate 66 and has the same function as the link 70. 110 The lower end of the lever 75 co-operates with a bifurcated plate 76 to bring the cam plate 66 into a plurality of adjusted positions with respect to the platen arm 46. The bifurcated plate 76 has a comparatively long 115 bifurcation 77 and a comparatively short bifurcation 78 (Figs. 1, 8 and 15). It will be noted that the bifurcated plate 76 is slidably journaled in a block 80 mounted upon the work-table 31 and that it can be moved 120 into a position wherein the bifurcation 77 alone will lie in the path of the lever 75 or into a position wherein both bifurcation 77 and 78 will lie in the path of the lever 75. A lever 81 pivotally secured to the bifurcated 125 plate 76 by a pin 82 is pivotally mounted upon the work-table 31, a pin 83 being provided for this purpose. That end of the lever 81 which is remote from the bifurcated plate 76 carries an anti-friction roller 84 130

adapted to be engaged by a cam bar 85. The cam bar 85 is rigidly secured to a disk 86 rotatably journaled upon a vertically disposed shaft 87. The cam bar 85, when rotated 5 around the axis of the shaft 87, is adapted to displace the lever 81 in a counter clock-wise direction (Figs. 1, 8 and 15) around the axis of the pin 83 against the action of a tension spring 88 which has one of its ends 10 fastened to the lever 81 by means of a pin 89, the other end of the spring being secured to the work-table 31 by a pin 90. The pin 89 passes through an aperture 91 in a bar 92 which serves to secure the pin 83 to the work-table 31. The pin 89 and the aperture 91 co-operate to limit angular displacement of 15 the lever 81 about the axis of the pin 83.

The bifurcated plate 76, the lever 81 and the cam bar 85 are so proportioned that 20 when the cam bar engages the anti-friction roller 84, the bifurcated plate 76 will be held in a position wherein both bifurcations 77 and 78 lie in the path of the lever 75 (Fig. 15). And when the cam bar 85 leaves the 25 roller 84, the spring 88 will bring the bifurcated plate 76 into a position wherein only the bifurcation 77 lies in the path of the lever 75 (Fig. 8).

Referring now to Fig. 4, it will be noted 30 that a helical spring 94 is adapted to hold the rollers 68 in engagement with the lower surface of the cam plate 66. It will also be noted that the cam plate 66 is recessed to provide a dwell 95 which would permit the 35 spring 94 to draw the platen roller 49 away from the work-table 31 if the platen mechanism were shifted to bring the rollers 68 into alignment with the dwell 95. The forward portion of the lower surface of the cam 40 plate 66 also forms a dwell which is indicated by the reference character 96.

Fig. 5, if compared with Fig. 4, illustrates 45 the manner in which the platen roller 49 can be brought into a position enabling it to take an impression from a printing device 97 indicated in dotted lines in Fig. 5. The platen roller 49 is brought to this position when the driven member 37 of the clutch is rotated 50 sufficiently to bring the operating member 41 into the position wherein it is shown in Fig. 5. The cam slot 43 in the operating member 41 co-operates with the anti-friction roller 44, while the operating arm 41 is being brought from the position shown in Fig. 4 55 into the position wherein it is shown in Fig. 5, to displace the platen arm 46 about the axis of the shaft 47. Further displacement of the operating member 41 in a counter clock-wise direction from the position wherein it is shown in Fig. 5 will permit the anti-friction roller 44 to engage a dwell 43^a of the cam slot 43 to hold the platen arm 46 stationary so that the roller 49 may be drawn 60 across the face of the printing device to take an impression therefrom. The platen roller 65

49 is drawn across the face of the printing plate by means of the block 59. It is apparent that continued displacement of the operating arm 41 in a counter clock-wise direction (Fig. 5) will cause the link 63 to 70 rotate the block 59 about the axis of the shaft 47 until the lug 61 engages and angularly displaces the lever 58. Such angular displacement of the lever 58 results in a corresponding angular displacement of the 75 sleeve 54, the lever 58 being connected to the arm 56 of the sleeve by the link 57. As the sleeve 54 is operatively connected to the platen roller 49 by the arm 53 and the lever 51, the sleeve is adapted to draw the platen 80 roller across the printing plate and into the position indicated in dotted lines in Fig. 5. When the operating arm is returned to its normal position, it restores the platen arm and the platen roller to their normal positions, the normal positions of these parts being illustrated in Fig. 4.

An inspection of Figs. 4 and 5 will show that in Fig. 5 the cam plate 66 occupies a different position relative to the platen arm 90 than it occupies in Fig. 4. This change of positions is brought about by the bifurcated plate 76 which in the full line positions in Figs. 4 and 5 is considered to be in a position wherein both bifurcations 77 and 78 lie 95 in the path of the lever 75. Therefore, when the operating arm 41 is angularly displaced in a counter clock-wise direction (Fig. 4) at the beginning of a cycle of operations, the lever 75 will engage the bifurcation 78 to 100 rotate the frame 72 about the axis of the pin 55. The frame 72, when so rotated, will draw the cam plate 66 from its position in Fig. 4 to its position in Fig. 5, the cam plate being connected to the frame 72 by the links 70 and 70^a. When the operating arm 41 returns to its normal position, the bifurcation 77 will cause the lever 75 to rotate the frame 72 to restore the cam plate 66 to its normal position.

If, in a manner and by means hereinafter described, the printing machine has been adjusted to present each printing device to the platen a plurality of times, the bifurcated plate 76 is reciprocated, by means of the lever 81 and the cam bar 85, to bring the bifurcation 78 into the path of the lever 75 during alternate downward strokes of the platen arm 46. The arrangement is such that when the platen roller is brought downward to take the first impression from a printing device, the bifurcation 78 is withdrawn from the path of the lever 75 and the cam plate 66 is left in the relative position in which it is shown in Fig. 4. Then, when the platen roller 49 is drawn across the printing device to bring it into a position indicated by dotted lines in Fig. 5, the rollers 68 will leave the dwell 96, thus permitting the spring 94 to raise the platen roller 49 125 130

from the printing device a distance which is gauged by the roller 68 and the dwell 95. This construction permits the platen roller 49 to draw away from the printing device 5 after it has taken an impression of a selected portion of the printing device. When the platen roller is brought down to make the second impression of the printing device, the bifurcation 78 is brought into the path of 10 the lever 75 to bring the cam plate 66 into the position wherein it is shown in full lines in Fig. 5. The platen roller may then take an impression of the remaining information carried by the printing device. 15 When the printing machine is adjusted to present each printing device to the platen a single time, the bifurcated plate 76 is reversed, so that its bifurcation 77 is disposed in the path of the lever 75 at all times (Fig. 20 25). The cam plate 66 will then be brought into the position shown in full lines in Fig. 5 and each time that the platen roller 49 takes an impression from a printing device the impression will include all the information 25 carried by the device.

The printing device and the printing device feed mechanism.

Fig. 26 illustrates a printing device of 30 the type which I prefer to employ in connection with my improved printing machine. As shown, the printing device 97 preferably comprises a metallic frame 98 on which are secured a plurality of type plates 35 99 and 100, together with a card 101 which carries the name and address of the holder of title of certain land or property. The information carried upon the card 101 is duplicated in suitable type upon the type plate 99. The type plate 100 is adapted to 40 carry a description of the land or other property. A printing device 97 having both a type plate 99 and a type plate 100 is termed a "leader." When the description of 45 the property held by one title owner is spread over several printing plates, a "leader" plate is provided having type plates 99 and 100 which carry information of the character described above. The remaining plates of the entry are not provided 50 with type plates 99 as I prefer to spread the information upon the type plates 100 of the several printing devices. It is not necessary to make a plurality of impressions of 55 the name and address of the holder of title. Printing devices that are not provided with a type plate 99 are termed "followers." Thus, an entry may consist of a single "leader" printing device or it may consist 60 of a "leader" printing device and several "follower" printing devices. Each of the follower printing devices is provided with a tab 102 which is indicated in dotted lines in Fig. 26, the tab being of the type com-

monly employed upon printing devices of 65 this character.

Referring now to Figs. 1, 2 and 3, the reference character 103 designates a magazine in which the printing devices are placed and from which they are fed, one by one, 70 to a printing position beneath the platen roller 49. The means for feeding the printing devices to the printing position comprises a pair of bars 104 which are slidably journaled in the work-table 31 and which are reciprocated to advance the printing devices in a step by step manner. As best 75 shown in Fig. 3, the bars 104 are each provided with a shoulder 105 adapted to withdraw printing devices from the magazine 80 103. The bars are also provided with dogs 106 which cooperate with dogs 107 pivotally secured in the work-table 31 to advance the printing plates to the printing position (Fig. 10). This construction is well known 85 and a detail description thereof need not be given. However, the bars are rigidly secured to a cross head 108 which is connected by means of a link 109 to a lever 110 journaled upon a shaft 111. The shaft 111 is fastened in the frame 30 and has its axis disposed parallel to the axis of the shaft 47 (Fig. 10). The lever 110 is provided with an elongated hub 112 which carries an 90 integral arm 113 and an integral lever 114, the lever 114 having a push rod 115 pivotally secured to it by means of a pin 116. The push rod 115 controls the operation of 95 a numbering machine which forms a part of my improved printing machine and will 100 be described below. The arm 113 is adapted to be engaged by a latch member 117 pivotally secured to a lever 118 by a pin 119, the lever 118 being pivotally mounted intermediate its ends upon the shaft 111. The lower end of the lever 118 is bifurcated 105 to receive one end of a link 119, the other end of the link 119 being pivotally secured to a lever 120 which is rigidly secured to the shaft 47. A bent plate 121 secured to the lever 120 carries an anti-friction roller 122 adapted to co-operate with the aforementioned numbering machine mechanism. The anti-friction roller 122 is rotatably 110 journaled upon an eccentric pin 123 which permits the roller to be brought into a plurality of adjusted positions with respect to the numbering machine mechanism. As shown in Figs. 4, 5 and 10, a lever 124 rigidly secured to the shaft 47 has its free end 115 pivotally secured, by means of a pin 125, to a lever 126 which is in turn pivotally secured to the operating member 41 by a pin 127. This construction permits the operating member 41 to oscillate the shaft 47 when the operating member is itself oscillated by means of the pitman 38 and the driven member 37 of the clutch. The shaft 47 will 120 125

in turn oscillate the lever 120 to impart an oscillatory motion to the lever 118 through the medium of the link 119. When the lever 118 is angularly displaced in a counter 5 clock-wise direction (Fig. 3) the latch member 117 is adapted to displace the arm 113, together with the integrally formed levers 110 and 114, around the axis of the shaft 111 unless the latch member 117 is disengaged 10 from the arm 113 by suitable means, but granting that the latch member 117 remains in engagement with the arm 113, the lever 110 will impart a reciprocatory motion to the bars 104 through the medium of the link 119 and the cross head 108, the integral levers 110 and 114 and their integral arm 113 being restored to their normal positions by 15 means of a lug 128 projecting laterally from the lever 118 and adapted to engage the lever 110. I employ the term "normal" to describe the positions that the parts assume 20 at the end of each cycle of operations.

The latch member 117 is constantly in engagement with the arm 113 when the 25 printing machine is adjusted to present each printing device to the platen roller for a single impression. But when the printing machine is to present each printing device to the platen roller a plurality of times, 30 it is necessary to hold the latch member 117 disengaged from the arm 113 during each alternate cycle of operations so that each printing device will remain in the printing position during two consecutive cycles of 35 operations. I have provided means having this function and this means preferably comprises a bent rod 129 which has one of its ends pivotally secured in the latch member 117 and the other of its ends journaled in a 40 U-shaped bracket 130, the latter end of the bent rod being adapted to engage the teeth of a ratchet wheel 131 (Fig. 6). The ratchet wheel 131 is rotatably journaled upon a pin 132 which projects from the frame 45 30 and also journals a lever 133 to which the U-shaped bracket 130 is pivotally connected by a pin 134. The lever 133 is provided with an extension 135 disposed in the path of an anti-friction roller 136 carried by an arm 137 formed integral with the platen arm 46. The construction is such that the anti-friction roller 136 will angularly displace the lever 133 about the axis of the pin 132 whenever the platen arm 50 55 brings the platen roller 49 into its lowermost position. The lever 133 is restored to its normal position by means of a helical spring 138 having one of its ends secured to the lever 133 and the other of its ends secured 60 to a bracket 139 formed integral with the frame 30. Angular displacement of the lever 133 by means of the anti-friction roller 136 will be accompanied by rotation of the ratchet wheel 131 as the bent rod 129 65 will engage a tooth of the ratchet wheel

and angularly displace the ratchet wheel through an angle which is substantially equal to the angle through which the lever 133 is displaced. It will be noted that the teeth of the ratchet wheel 131 are formed by 70 a plurality of notches of unequal depth, the deeper notches being identified by the reference character 140, and the shallow notches being identified by the reference character 141. In Fig. 6, the bent rod 129 75 is shown in a position in full lines, wherein it rests in one of the deeper notches 140. When the bent rod 129 is so positioned, the latch member 117 remains in engagement with the arm 113, but as the shallow notches 80 alternate with the deeper notches, it is apparent that if the ratchet wheel is advanced a single step, the bent rod 129 will rest in a shallower notch when the lever 133 is again restored to its normal position. The rod 129 will then hold the latch member 117 disengaged from the arm 113 and on the following down-stroke of the platen arm 46 the printing device feeding mechanism 85 will fail to bring a new printing device into the printing position, thus enabling the platen roller 49 to take a second impression of the printing device which occupies the printing position.

The above described mechanism which 90 comprises the latch member 117, the bent rod 129, the ratchet wheel 131, and the lever 133 is generally known as the "duplicating mechanism".

It is evident that the duplicating mechanism must be held in some adjusted position if the latch member 117 is to remain constantly in engagement with the arm 113 when the printing machine is adjusted to present each printing device to the platen roller for a single impression. This is accomplished by means of a push rod 142 slidably journaled in the bracket 139 and adapted to be locked in a plurality of positions with respect to the bracket, the bracket being provided with notches 143 and 144 to receive a pin 145 projecting from the push rod. A tension spring 146 is adapted to hold the pin 145 in either of the notches 143 and 144, the spring 146 having one of its ends fastened to the pin 145 and the other of its ends fastened to the bracket 139. In Fig. 6, the push rod 142 is shown in the position wherein it must be placed when the printing machine is to present each printing device to the platen a plurality of times. I have also shown, in dotted lines, the position the push rod must occupy when the printing machine is adjusted to make a single impression of each printing device. The operator may bring the push rod from one of its adjusted positions to the other of its adjusted positions by angularly displacing it about its axis to disengage the pin 145 from a particular notch and then draw- 115 120 125 130 135

ing or pushing the push rod into the desired position. When the push rod 142 occupies the position wherein its pin 145 rests in the notch 144, the lever 133 is held in a position 5 which prevents the roller 136 from engaging the extension 135 of the lever. The bent rod 129 will then be disposed as shown in dotted lines in Fig 6, the ratchet wheel being manually positioned, if necessary, to have 10 the bent rod rest in one of the shallow notches 141. When the duplicating mechanism is so arranged, the latch member 117 will remain in engagement with the arm 113 at all times and each printing device will 15 be presented to the platen for a single impression.

The ratchet wheel 131 is provided with a holding pawl 147, which is yieldingly held in engagement with the teeth of the ratchet 20 wheel by means of a spring 148. The purpose of this construction is obvious.

The blank holding, feeding and shifting mechanism.

25 In Fig. 1 I have indicated, in dotted lines, a blank 150 which is firmly held in a blank holder, the reference character 151 being employed to designate the blank holder in its entirety.

30 Referring to Figs. 1 and 11, the blank holder 151 preferably comprises a bar 152 having laterally projecting teeth 153 and having an integral post 154 at one of its ends. A clamping member 155 is pivotally secured to the post 154 by a pin 156 and may be locked against displacement relative 35 to the bar by means of a latch 157, the latch 157 being pivotally mounted in the clamping member 155 and being provided with a compression spring 158 which tends to hold it in engagement with the bar 152 when the clamping member and bar are in the relative 40 positions shown in Fig. 11. The clamping member 155 is U-shaped in cross section and 45 accommodates a plurality of spring fingers 159, which are rigidly secured to the clamping member by means of rivets 160. The spring fingers 159 and the bar 152 are adapted to clamp the blank 150 to them. A gauge 50 plate 161 rigidly secured to the bar 152 provides means whereby the blank 150 may be properly positioned in the blank holder, and a bent plate 162 carried by the gauge 55 plate 161 is adapted to engage a stop lever 163 which is pivotally mounted intermediate its ends upon the work-table 31 by a pin 164. Because of the length of the blank holder 151, I find it advantageous to provide the clamping member 155 with a dowel pin 60 165 which rests in a depression 166 in the bar 152 when the clamping member 55 is locked to the bar 152.

Means are provided on the blank holder for automatically opening it when the latch 65 157 is released. This means comprises a

tension spring 151^a which has one of its ends secured to the post 154 and the other of its ends secured to the clamping member 155. The blank holder 151 is slidably journaled as a unit in a way 167 which is in turn 70 slidably journaled upon a plurality of guide bars 168, the way 167 being provided with a plurality of apertured lugs 169 for this purpose (Figs. 1 and 10). It is apparent that the blank holder 151 may be displaced 75 longitudinally of the machine by sliding it in the way 167 and that the blank holder 151, together with the way 167, may be displaced transversely of the machine by sliding them along the guide bars 168. 80

The means for displacing the blank holder longitudinally of the machine to feed the blank, in a step by step manner, to the printing position comprises an elongated pawl 170 pivotally secured to a lever 171 by 85 a pin 172 (Figs. 1 and 10). The lever 171 is pivotally mounted intermediate its ends upon the work-table 31 by a pin 173. The free end of the pawl 170 is adapted to engage the teeth 153 of the bar 152, a tension spring 174 tending to hold the pawl in engagement with the teeth. The spring 174 has one of its ends fastened to the pawl and the other of its ends fastened to the way 167 by a pin 175. Means are provided 90 for oscillating the lever 171 to cause the pawl 170 to advance (in a step by step manner) the blank holder toward the rear end of the printing machine, the throw of the lever and the spacing of the teeth being proportioned to feed the blank a proper distance each time the blank holder is to be advanced. 95

A link 176 pivotally secured to the right hand end (Fig. 1) of the lever 171 forms a 100 part of the means for oscillating the lever 171. The forward end of the link 176 is pivotally secured to a segmental gear 177 by a pin 178, the segmental gear being rigidly secured to the aforementioned shaft 87 (Figs. 8 and 9). The segmental gear 177 meshes 105 with a segmental gear 179 which is rotatably journaled upon a stud shaft 180 carried by a bracket 181 supported upon the work-table 31. The segmental gear 179 is connected by 110 means of a link 182 to the platen arm 46. The proportions are such that each upward stroke of the platen arm will result in an angular displacement of the lever 171 sufficient to advance the blank holder 151 a single space. Of course, the pawl 170 is advanced 115 along the teeth 153 during the downward stroke of the platen arm 46, it being understood that the segmental gear 177 is oscillated by means of the segmental gear 179, the link 182 and the platen arm 46, and that the link 176 is given a reciprocatory motion. 120

In Fig. 1 I have shown the mechanism of the printing machine adjusted to present each printing device to the platen a plurality of times. The lever 171 is pivotally 125 130

mounted by means of a pin 173 which passes through an aperture 173^a in the lever. The lever is also provided with apertures 173^b and 173^c, and corresponding screw threaded holes are provided in the work-table. The purpose of this construction will presently appear. It will be noted that the pawl 170 is also provided with a pivoting aperture 170^a.

As set forth above, the reason for having mechanism which permits each printing device to be presented to the platen a plurality of times is to enable the printing machine to make an impression from a printing device in one column of the blank and to make a second impression thereof in another column on the blank. As part of the information carried by the printing device is placed in the first column and the remainder of the information carried by the printing device is placed in the second column, I employ the term "divided printing" to describe this act of dividing the information between a plurality of columns of the blank, each portion of information being printed by a separate stroke of the platen.

When it is desired to replace the blank holder 151 with a blank holder having teeth of different spacing, the pawl 170 may be held out of engagement with the teeth 153 by means of a lever 253^a which is pivotally mounted upon the way 167 by a pin 253^b. A tension spring 253^c normally holds the lever 253^a in a position which permits the pawl 170 to engage the teeth 153. However, if the lever 253^a is rotated a slight distance in a counter clock-wise direction (Fig. 1) the pawl will be moved away from the teeth and the blank holder 151 may be withdrawn from the way.

My improved printing machine preferably comprises means for shifting the blank in a direction normal to the direction in which the blank is fed by the above described mechanism comprising the pawl 170. The shifting means comprises a plurality of bars 185 and 186 arranged transversely of the printing machine. Each of the bars 185 and 186 has its left-hand end (Fig. 1) secured to the way 167, the right-hand end of each bar being pivotally secured to one arm of one of a plurality of bell cranks 187 and 188. The bell cranks 187 and 188 are pivotally mounted upon the work-table 31 by means of pins 189. The other arms of the bell cranks 187 and 188 are pivotally secured to a bar 190 by pins 191. The bar 190 is disposed longitudinally of the printing machine and is operatively connected to the aforementioned disk 86 by means of a link 192, the link 192 having one of its ends pivotally secured to the bar 190 by a pin 193 and the other of its ends pivotally secured to the disk 86 by a pin 194 (Figs. 8 and 9).

The disk is adapted to be rotated inter-

mittently to reciprocate the bar 191 so as to oscillate the bell cranks 187 and 188 which in turn reciprocate the bars 185 and 186. When the bars 185 and 186 are reciprocated they will shift the way 167 and the blank holder 151 from the position wherein they are shown in full lines in Fig. 1 to a position which is diagrammatically shown by dotted lines in the same figure, and after leaving them (the way and the blank holder) in the dotted line position for a brief period of time will return them to the position indicated in full lines.

The means for rotating the disk 86 intermittently comprises a pawl 195 pivotally mounted, by a pin 196, upon a downwardly extending lug 197 formed upon the segmental gear 177. The disk 86 is provided with diametrically disposed teeth 198 and 199 (Fig. 15), the pawl 195 being shown in engagement with the tooth 199 in Fig. 8. When the printing machine is in operation, the segmental gear 177 is oscillated by reason of its connection with the platen arm 46 by way of the segmental gear 179 and the link 182. The segmental gear 179 is displaced through an angle of substantially 180 degrees, which displacement permits the pawl 195 to engage the teeth 198 and 199 alternately and to advance the disk 86 one-half of a revolution at the time. A compression spring 200 tends to hold the pawl 195 in engagement with the disk 86. To hold the disk 86 immovable during the return strokes of the pawl 195 I provide an anti-friction roller 201 (Fig. 8) mounted upon a lever 203 which is pivotally mounted upon the work-table 31 by a pin 204. The anti-friction roller 201 is adapted to co-operate with a plurality of diagrammatically disposed notches 205 and 206 cut into the disk 86, a tension spring 207 being adapted to draw the anti-friction roller 201 into a notch whenever a notch registers with the anti-friction roller.

From the foregoing description it becomes apparent that whenever the printing mechanism on the printing machine is arranged in the manner illustrated in Figs. 1, 8 and 9, the movement of the platen will cause the blank holder to shift back and forth in a direction normal to the direction in which the blank is fed to the platen by means comprising the pawl 170 which is also operatively connected to the platen. The train of mechanism which includes the platen mechanism, the blank feeding mechanism and the blank shifting mechanism, is so timed that the platen arm may descend and allow the platen roller 49 to be drawn across the printing device while the blank holder is in the position wherein it is shown in full lines in Fig. 1. Then, on the following up-stroke of the platen arm the blank holder will be shifted to the position shown in dotted lines

so that on the immediate following down-stroke on the platen arm the impression taken by the platen roller will follow in another column on the blank. Then, as the platen arm returns to its normal position, the blank holder will return to the position shown in full lines and the following printing device will be fed into the printing position.

10 The printing machine may be adjusted to do single column work. The pawl 195 is then thrown into a position which prevents it from engaging the teeth 198 and 199 of the disk 86. This is done by means of an eccentric pin 210 rotatably mounted in the lug 197 of the segmental gear 177 (Figs. 8 and 9). A pin 211 which projects from the eccentric pin 210 may be employed to rotate the eccentric pin from a position wherein the pin 211 rests against a stop pin 212 to a position wherein the pin 211 rests against a stop pin 213. When the pin 211 rests against the stop pin 212, the pawl 195 will engage the teeth 198 and 199 of the disk 86, but when the pin 211 engages the stop pin 213, the pawl 195 will be held in a position wherein it can not engage the teeth. It follows then that the shifting mechanism may be disconnected from the platen arm 25 by the act of bringing the pin 211 into engagement with the stop pin 213 and that this act will also prevent the bifurcated plate 76 from being retracted as care is taken to leave the cam bar 85 in a position wherein it holds the bifurcated plate in the position indicated in Fig. 15. However, the means for advancing the blank holder longitudinally of the printing machine will continue to function as the link 176 is directly connected to the 30 segmental gear 177 and it is this link which operates the pawl 170 by way of the lever 171. But it is necessary in this adjustment of the machine to replace the blank holder 151 with a blank holder of substantially 35 identical construction but having teeth of different spacing so that the blank will be advanced a greater distance after an impression has been taken from a printing device. This change is required because all 40 of the information carried upon the printing device is placed in a single column. In addition to replacing the blank holder 151, it is also necessary to move the pivoting pin 173 into the aperture 173^a or into the aperture 173^c, the table top being provided with suitably threaded holes which permit this adjustment. It is apparent that if the pivoting pin 173 is moved into the aperture 173^b or into the aperture 173^c, the pawl 170 45 will be given a longer stroke. Which one of the apertures 173^b and 173^c is to be employed is determined by the distance it is desired to advance the blank after each operation of the platen roller. When either one of these 50 apertures is used, it becomes necessary to bring the aperture 173^a of the pawl 170 to the pin 172 so as to shorten the effective length of the pawl.

It is desirable, in divided printing, to cover or mask temporarily any part of the printing device of which an impression is not to be made during any particular operation of the platen roller. I have provided means of this character in my improved printing machine. The mask proper is a substantially rectangular sheet of metal 70 which is identified by the reference character 215 and which is provided with a substantially rectangular aperture 216 (Fig. 1). The aperture 216 may be registered with a printing device in printing position so as to permit the platen roller 49 to take an impression of all of the information carried by the printing device, or it may be brought into a plurality of adjusted positions, either 75 of which positions permits the platen roller to take an impression of a selected portion of the printing device. The means for operating the mask comprises a lever 217 which has one of its ends connected to the mask by a link 218. The lever 217 is pivoted intermediate its ends upon the work-table 31 by a pin 219, and the other end of the lever has pivotally secured to it a link 221 by means of a pin 220. The link 221 connects the link 80 217 with the bar 190 through the medium of a pin 222. As the bar 190 is given a reciprocatory motion when the printing machine is adjusted for divided printing, it follows that this reciprocatory motion will be imparted 85 to the mask 215 through the medium of the lever 217. The aperture 216 will be positioned to uncover the type plate 100 when the first impression is taken by the platen roller 49 and will then move into a position 90 wherein it uncovers the type plate 99 when the second impression is taken by the platen roller.

When the platen is to take a single impression from each printing device and is to 95 transfer all the information contained thereon upon the blank, the pin 222 is withdrawn and the link 221 is brought into the position wherein an aperture 223 in the link receives a pin 224 projecting upwardly 100 from the work table 31. The mask is then held in a position wherein it permits the platen roller to make a single impression of all of the information carried by a printing device in printing position.

As shown in Figs. 1 and 3, I preferably provide a plurality of sheet metal plates 225 and 226 upon which the blank may rest as it is being advanced by the blank feeding mechanism. The plate 226 is secured to the 105 forward end of the work-table 31 and the plate 225 is disposed at the other end of the work-table, the plate 225 being curved to keep the blank from contact with the several levers disposed on the work-table.

In Fig. 1, the reference character 227 designates a cam which is carried by the blank holder 151 and which is adapted to engage a pin 228 projecting upwardly from the pawl 170. This engagement is made when the blank holder has been advanced to its rearmost position and the function of the cam is to move the pawl 170 out of engagement with the teeth 153 of the blank holder 10 so that no injury will occur to the machine.

At this point in the description, it is well to point out that the gauge plate 161, carried by the blank holder 151, and a gauge bar 261^a provide means for correctly positioning the blanks in the printing machine. The gauge bar 261^a is secured to the work-table 31 by a plurality of screws 261^b. In Fig. 1, the gauge bar 261^a is shown in full lines in the correct position for divided printing. When the machine is adjusted for single column work, the gauge plate is positioned, as indicated by dotted lines in the same figure, a plurality of threaded holes 261^c being provided in the table top 25 for this purpose.

Stop devices.

The aforementioned lever 126 pivotally mounted upon the operating arm 41 is provided at its free end with an anti-friction roller 230 adapted to ride in a slot 231 in one end of a lever 232 which is pivotally mounted intermediate its ends by a pin 233 (Figs. 2 and 4). Pivotally connected to the other end of the lever 232 is a vertically disposed rod 234, the rod 234 being loosely mounted in a bell crank 235 which is pivotally secured to the magazine 103 by a pin 236 (Fig. 14). A helical spring 237 disposed around the rod 234 tends to rotate the bell crank 235 in a counter clock-wise direction (Fig. 14). The lower end of the helical spring 237 bears upon one arm of the bell crank 235 and its upper end bears upon a washer 239 which is adjustably positioned upon the rod 234 by means of a nut 240. The rod 234 passes through an arm 241 of the bell crank, the other arm of the bell crank being designated by the reference character 242 and being provided with a finger 243 which tends to enter the printing device compartment in the magazine 103 when under the action of the spring 237. In Fig. 14, the finger 243 is held against the lowermost one of a plurality of printing devices which are stacked in the magazine. It is apparent that if these printing devices are withdrawn from the magazine, the finger 243 will enter the printing device compartment, thus permitting the bell crank to withdraw a plate 244 from a position wherein it engages a lever 245 pivotally secured at one end to the work-table 31 by a pin 246 (Figs. 2 and 14). The plate 244 is loosely secured to the bell crank arm 242

by a plurality of machine screws 247, the plate being provided with comparatively large apertures through which the screws pass. A compression spring 248 seated in a recess 249 formed in the arm 242 tends to hold the plate 244 in the position wherein it is shown in Fig. 14 so that the lever 245 can not be rotated in a clock-wise direction (Fig. 2) about its axis 246. The forward end of the lever 245 is connected to the pivoted lever 35 of the clutch by means of a link 250 and the construction is such that yielding means therein tends to rotate the lever 245 in a clock-wise direction (Fig. 2) through the medium of the link 250. If, while the printing machine is in operation, the lever 245 is rotated in a clock-wise direction (Fig. 2) the printing machine will come to a full stop at the end of the particular cycle during which the angular displacement of the lever 245 takes place. It is apparent then that if the last printing device in the magazine were withdrawn therefrom during a cycle of operations, so as to permit the bell crank 235 to withdraw the plate 244 from engagement with the lever 245, the lever 245 would be released and the driven member of the clutch would be disengaged from the driving member of the clutch at the end of the cycle.

Referring now to Fig. 1, it will be noted that the lever 163 is provided with a plurality of anti-friction rollers 251 and 252, the anti-friction roller 251 being adapted to be engaged by the bent plate 162 carried by the blank holder 151. The anti-friction roller 252 rides upon a cam 253 formed upon a lever 254 which is pivotally mounted, by means of a pin 255, to swing in a substantially horizontal plane. One end of the lever 254 is adapted to dislodge the plate 244 from its position on the lever 245 when the lever 163 is rotated in a clock-wise direction (Fig. 1). If the lever 163 is so rotated, the roller 252 will ride upon the cam 253 and cause the lever 254 to rotate in a counter clock-wise direction (Fig. 1), the lever 254 being rotated through a comparatively small angle but sufficiently large to permit the lever 254 to release the lever 245 (Fig. 14).

A rod 256 having one of its ends loosely hooked upon one end of the lever 254 has the other of its ends pivotally secured to a lever 257 which is pivotally mounted upon the work-table 31 by means of a pin 258. The forward end of the lever is conveniently disposed so that the operator of the printing machine may angularly displace it in a clock-wise direction (Fig. 1) to cause the lever 254 to release the lever 245. In practice, the operator holds the lever 257 against a stop 260 when it is desired to have the printing machine come to a full stop at the end of each cycle of operations. If the lever 130

257 is permitted to remain in the position wherein it is shown in Fig. 1, the machine will operate continuously until all of the printing devices have been withdrawn from 5 the magazine or until the bent plate 162 engages the anti-friction roller 251 upon the lever 163. The lever 163, the lever 254 and the lever 257 are normally held in the positions wherein they are shown in Fig. 1 by 10 means of a tension spring 261 which has one of its ends fastened to the lever 254 and the other of its ends fastened to a bar 262 projecting from the lever 163.

15 *The numbering machine and the mechanism for actuating and controlling the numbering machine.*

It will be recalled that a push rod 115 has one of its ends pivotally secured to the lever 20 114 which is formed integrally with the arm 113 and the lever 110, the lever 110 being connected to the bars 104 by a link 109 and a cross head 108. It will also be recalled that the integral levers 110 and 114 are oscillated 25 once during each cycle of operations if, during each of these cycles a printing device is fed into the printing position. In other words, the integral levers 110 and 114 make one oscillation for each cycle of operations 30 when the printing machine is adjusted to present each printing device to the platen a single time. And when the machine is adjusted for divided printing the integral levers 110 and 114 oscillate only during alternate cycles of operations. This result is obtained 35 through the medium of the pawl or latch member 117 which is controlled by the duplicating mechanism.

The push rod 115 projects forwardly from 40 the lever 114 and is supported intermediate its ends upon an anti-friction roller 265 which is carried upon the arm 266 of a bell crank lever 267. The other arm of the bell crank lever 267 is identified by the reference 45 character 268 and is engaged when in its normal position by the aforementioned anti-friction roller 122 (Figs. 3, 16, 17, 18 and 19). The normal position of the bell crank lever 267 is considered to be that position to 50 which it returns at the end of each cycle of operations, the normal position being shown in Figs. 3 and 16. The bell crank lever 267 is held in its normal position by the weight 55 of the push rod 115 which tends to rotate the bell crank lever in a clock-wise direction (Figs. 3 and 16). It will be noted that the push rod 115 does not directly engage the anti-friction roller 265 but that the push rod is provided with a shoe 269 adapted to ride 60 upon the anti-friction roller. The bell crank lever 265 is pivotally journaled upon a shaft 270 journaled in the frame 30. The shaft 270 is of rectangular cross section at 271 to 65 permit a lever 272 and a lever 273 to be secured to it by means of machine screws 274

and 275 respectively. The lever 273 is provided with a lug 276 adapted to engage a lug 277 formed upon the bell crank lever 267, and a tension spring 278 tends to hold the lever 273 in a position wherein its lug 276 70 will rest against the lug 277. The spring 278 has one of its ends secured to the lug 276 and the other of its ends secured to the lever 267 by means of a pin 279. Pivotally secured to the lever 273 by means of a pin 280 is a latch 281 which has a shoulder 282 adapted to be drawn into engagement with the lug 277 by a tension spring 283, the tension spring 283 being permitted to bring the shoulder 282 into engagement with the lug 280 75 when the lever 273 is angularly displaced about the axis of the shaft 270 to bring it into the position wherein it is shown in full lines in Fig. 18. The tension spring 283 has one of its ends fastened to the lever 273 by 80 means of a pin 284 and it has the other of its ends fastened to the latch 281 by means of a pin 285. Means is provided for angularly displacing the lever 273 about the axis of the shaft 270, the means being adapted to 85 rotate the shaft to obtain this result. The means comprises a vertically disposed rod 286 which is slidably journaled in the work-table 31 and which has its lower end supported by the lever 272. The upper end of 90 the rod 286 supports a determining finger 287 pivoted in the work-table 31 by a pin 288. It is apparent that if the free end of the determining finger 287 is depressed the shaft 270 will be rotated in a clock-wise direction (Fig. 16) and that the lever 273 will 95 be brought into a position which permits the latch 281 to be drawn upwardly by the spring 283 so that its shoulder 282 may engage the lug 277. This condition is illustrated in full lines in Fig. 18. A stop pin 100 105 289 projecting from the frame 30 limits the angle through which the lever 273 may be displaced in a clock-wise direction (Fig. 16), the stop pin 289 being adapted to be engaged 110 by the lug 276.

Resting upon the forwardly projecting end of the lever 281 is an arm 290 of a bell crank lever 291 which is pivotally mounted upon a pin 292 projecting from the frame 115 30. The other arm 293 of the bell crank lever 291 is disposed in the path of a roller 293^a carried by the push rod 115, and when the push rod moves forward the roller is adapted to engage the arm 293 to cause 120 the arm 290 to depress the forwardly extending end of the latch 281. Therefore, if the shoulder 282 is resting against the lug 277, the bell crank lever 291 may be rotated in a counter clock-wise direction (Fig. 16) 125 by means of the roller 293^a to disengage the shoulder from the lug. The tension spring 278 will then tend to draw the lever 273 and the bell crank lever 267 into the relative positions in which they are shown in Fig. 130

16. A stop pin 290^a is provided to limit the movement of the crank lever 291.

Rigidly secured to the push rod 115 and disposed adjacent the forward end thereof 5 is a plate 294 upon which are pivotally mounted a plurality of dogs 295 and 296, the dog 295 being pivotally mounted upon the plate by means of a pin 297, and the dog 296 being pivotally mounted upon the 10 plate by means of a pin 298. The angle through which the dog 295 may be oscillated is limited by a pin 299 projecting from the plate 294 and entering a slot 300 formed in the dog. In a like manner, the angle 15 through which the dog 296 may be oscillated is limited by a pin 301 which projects from the dog and rides in a slot 302 formed in the plate 294. The dog 295 is provided with a downwardly extending pin 303 and the dog 20 296 is provided with an upwardly extending pin 304. A tension spring 305 tends to rotate the dog 295 in a counter clock-wise direction (Fig. 16) and the tension spring 306 tends to rotate the dog 296 in a counter 25 clock-wise direction (Fig. 16). The springs 305 and 306 tend to bring the dogs 295 and 296 into positions wherein their respective pins 303 and 304 rest against an eccentric pin 307, the eccentric pin 307 being rotatably 30 journaled in the plate 294 and being provided with a cross pin 308 to facilitate adjustment thereof. At certain times and under certain conditions the dog 296 is adapted to engage a shoulder 309 formed upon 35 a lever 310 which is pivotally mounted on the frame 30 by means of a pin 311. The dog 296, when it engages the shoulder 309, is adapted to rotate the lever 310 in a counter clock-wise direction (Fig. 16) which 40 will then in turn rotate a lever 312 in a clock-wise direction (Fig. 16). The lever 312 is pivotally mounted intermediate its ends upon the frame 30 by a pin 313. The upper end of the lever 312 is connected to 45 the free end of a lever 314 by means of a link 315, the lever 314 being rigidly secured to a pin 316 rotatably journaled in the frame 30. Rigidly secured to the pin 316 so as to oscillate in unison with the lever 314 50 is a cam 317 having a substantially arcuate dwell 318 and a flattened portion 319. The cam 317 is adapted to support a numbering machine 320 which is carried as a unit upon the free end of a lever 321, the lever 321 being pivotally mounted in the work-table 55 31 by a pin 322. When the numbering machine is in its printing position it rests upon the arcuate dwell 318 of the cam 317, but when it rests upon the flattened portion 60 319 of the cam it will have dropped out of printing position. It is understood, of course, that the flattened portion 319 of the cam 317 may be brought into a proper position to support the numbering machine 320 65 and that these means may comprise the

dog 296, the lever 310, the lever 312, the link 315 and the lever 314. This result may be obtained by other means which will now be described.

The dog 295 is also adapted to withdraw 70 the numbering machine 320 from its printing position. For this purpose the dog 295 is provided with an undercut shoulder 323 adapted to engage an undercut shoulder 324 formed upon the lever 312. At certain 75 times during the operation of the printing machine the shoulder 323 will engage the shoulder 324 to rotate the lever 312 in a clock-wise direction (Fig. 16) which will in turn rotate the lever 314 in a counter clock-wise direction to align the flattened portion 319 of the cam 317 with the bottom surface 80 of the numbering machine. This condition obtains in Fig. 23. A latch 325 is adapted to lock the lever 312 in a position wherein 85 it causes the numbering machine 320 to be supported upon the flattened portion 319. The latch 325 is pivoted intermediate its ends upon the frame 30 by a pin 326 and is provided with a shoulder 327 at one of 90 its ends. The shoulder 327 is adapted to engage a shoulder 328 formed upon the lever 312 so as to lock the lever in the position wherein it is shown in Fig. 23, this position 95 of the lever 312 being the one the lever assumes when the numbering machine is lowered out of its printing position. A tension spring 329 tends to rotate the latch 325 in a counter clock-wise direction (Fig. 16) so 100 that the shoulder 327 will engage the shoulder 328 when the lever 312 is in the proper position to permit such engagement. To provide means for disengaging the shoulder 327 from the shoulder 328, the latch 325 is formed with an upwardly extending finger 105 330 which lies in the path of an anti-friction roller 331 carried upon an accumulator bar 332 which is pivotally mounted intermediate its ends upon the frame 30 by means 110 of a pin 333. The upper end of the accumulator bar 332 is connected to an accumulator lever 334 by a link 335, the accumulator lever 334 being rigidly secured to a shaft 334^a which forms part of the 115 accumulating mechanism of the numbering machine 320 and which carries the numeral wheels 336. The lower end of the accumulator bar 332 is provided with a block 337 which projects laterally from the bar and which is adapted to be engaged by an under- 120 cut shoulder 338 formed upon the forward end of the push rod 115. During the operation of the printing machine, the shoulder 338 will at times engage the block 337 to permit the push rod 115 to rotate the accumulator bar 332 in a counter clock-wise direction (Fig. 16) against the action of a tension spring 339 which has one of its 125 ends fastened to the accumulator bar by means of a pin 340, and which has the other 130

of its ends secured to the lever 312 by means of a pin 341. (It will be noted that the spring 339 tends to hold the lever 312 against a stop 312^a.) Such displacement of the 5 accumulator bar places the accumulating mechanism of the numbering machine in a condition which will allow it to function, that is, to accumulate, when the accumulator bar is returned to its normal position by the tension spring 339. It is apparent that the 10 anti-friction roller 331 will engage the finger 330 of the latch 325 when the accumulator bar is rotated in a counter clock-wise direction (Fig. 16) and that the shoulder 327 of the latch 325 will be drawn away from the 15 shoulder 328 upon the lever 312.

A link 342 may be employed to connect the lever 312 directly to the accumulator bar 332. The link 342 is permanently secured to the 20 lever 312 by a pin 343 which projects from the lever and rides in a slot 344 formed in the link. The forward end of the link is provided with a hook 345 which may be engaged with a pin 331^a adapted to rotatably journal 25 the anti-friction roller 331. The hook is shown so engaged with the pin 331^a in Fig. 16.

Operation.

30 I will first describe the operation of the printing machine when it is employed in divided printing, that is, for instance, the printing of tax lists wherein the names and the addresses of the holders of title are placed in one column and the descriptions of the 35 various parcels of land are placed in a second column. A tax list of this character is shown in Fig. 28, the names and the addresses of the holders of title being disposed in a column 350, descriptions of the 40 various parcels of land in a column 351, and the identifying numbers for the entries in a column 352.

The printing machine, when employed in 45 divided printing, is adjusted as shown in full lines in Figs 1, 6, 8 and 16, with an exception hereinafter set forth. It will be noted that the gauge bar 261^a is in its right hand position (Fig. 1) and that the push 50 rod 142 is in a position wherein its pin 145 rests in the notch 143 of the bracket 139 (Fig. 6). It will also be noted that the pin 211 of the eccentric pin 210 is positioned 55 against the stop pin 212 (Fig. 8) and that the eccentric pin 307 is so positioned that the spring 306 is permitted to hold the dog 296 in its uppermost position (Fig. 16). The hook 345 of the link 342 is shown in engagement 60 with the pin 331^a projecting from the accumulator bar 332. With the printing machine so adjusted the operator may place a proper blank (Fig. 28) in the machine, the blank being positioned by means of the gauge bar 261^a and the gauge plate 161, 65 the blank holder being brought into its

foremost position. Then after a supply of printing devices have been placed in the magazine 103, the operator may set the machine in operation by depressing the foot treadle (not shown) which is connected to 70 the pivoted lever 35 by the rod 36. The printing machine will then operate continuously until the motor 32 is stopped or until the level 257 is brought against the stop 260 (Fig. 1). The printing devices may consist 75 both of "leaders" and "followers", the "followers" being provided with tabs 102 but not being provided with type plates 99. As hereinbefore set forth, each entry may consist of a "leader" or of a "leader" and one 80 or more "followers", the "followers" carrying descriptions of additional parcels of land to be accredited to the holder of title of the parcel of land described upon the "leader". In practice, the printing machine is generally 85 turned over a few times to bring the first "leader" to the printing position before the blank is placed in the machine. When the machine has been set in operation, the first impression is taken from the printing 90 device in printing position, being an impression of the description of the property carried by the type plate 100. The identifying number is printed simultaneously. 95 The initial downward stroke of the platen arm 46 is accompanied by a downward movement of the push rod 115 as the oscillating shaft 47 will angularly displace the lever 120 (Fig. 16) to withdraw the anti-friction roller 122 from the arm 268 of the bell crank 100 lever 267. This permits the weight of the push rod 115 to angularly displace the bell crank lever in a clock-wise direction (Fig. 16). Therefore, the push rod drops until 105 its forward end rests against the lug which forms the shoulder 337 on the accumulator bar 332. The push rod 115 remains stationary during the remainder of the cycle in which the first impression is taken but returns to its normal position at the end of the 110 cycle as the anti-friction roller 122 again engages the arm 268 of the bell crank lever 267 at the end of the cycle. The reason that the push rod 115 does not move forward during this cycle is that the operator positions the 115 bent rod 129 in one of the shallow notches 141 of the ratchet wheel 131 before the machine is set in operation. This act prevents the latch member 117 from angularly displacing the arm 113 and its integral levers 110 and 120 125 114, the lever 114 being pivotally connected to the push rod 115. And as the lever 110 is not angularly displaced the printing device feed mechanism will not function to bring another printing device into the printing position, thus enabling the machine to take a second impression of the "leader" of which a first impression has been made. But it will be understood that the proper identifying number is printed during the first 130

impression of a "leader" as the numbering machine is not withdrawn from its printing position during that cycle. The position of the mask 215 during the first impression is 5 that indicated in Fig. 1.

During the down stroke of the platen 46 when the second impression is being taken of the "leader" in printing position (and for simplicity the following printing device 10 is assumed to be a "leader") the push rod 115 again drops into a position wherein it is aligned with the shoulder 337 on the accumulator bar 332. But as the bent rod 129 now engages one of the deeper notches 140 15 in the ratchet wheel 131, the latch member 117 is permitted to displace the arm 113 and its integral levers 110 and 114, which displacement causes the push rod 115 to displace the accumulator bar 332 in a counter clock-wise direction (Fig. 16). The accumulator 20 bar in turn angularly displaces the lever 312 in a clock-wise direction (Fig. 16) through the medium of the link 342. This displacement of the lever 312 results in a displacement 25 of the cam 317 allowing the numbering machine to drop out of its printing position. When the push rod 115 is returned to its normal position the spring 339 restores the accumulator bar 332, the lever 312 and the 30 cam 317 to their normal positions, the accumulator bar actuating the accumulating mechanism of the numbering machine through the medium of the link 335 and the lever 334. During this second impression 35 cycle the dogs 295 and 296 do not engage the shoulders 324 and 337 respectively but the lever 110 causes the printing device feed mechanism to bring the following printing device into printing position during the up-stroke of the platen arm 46.

It will of course be understood that the blank is shifted to the left (Fig. 1) after the first impression is taken so that the name of the holder of title will fall in the column 45 350 when the second impression is made. This movement is obtained by mechanism best shown in Figs. 1, 8, 9 and 11 and comprising the disk 86 which is rotated 180° during the upstroke of the platen arm 46 50 during the first impression, the disk 86 being adapted to oscillate the bell cranks 187 and 188 through the link 192 and the bar 190. The bell cranks 187 and 188 control the position of the blank holder 151 by means 55 of the bars 185 and 186 and it is the displacement of these bars that causes the blank to be shifted to the left (Fig. 1), during the upstroke of the platen arm in the first impression cycle. And from the foregoing de- 60 scribed description of this mechanism, it is apparent that the blank is returned to its right hand position (Fig. 1) during the upstroke of the platen in the second impression cycle.

65 The disk 86 also controls the mask 215 by

way of the link 192, the bar 190, the link 221, the lever 217 and the link 218. This train of mechanism shifts the mask in a proper direction during the upstroke of the platen arm in each cycle. 70

The means for aligning the information printed during the second impression cycle with that printed during the first impression cycle comprises the pawl 170 which is operatively connected to the segmental gear 177 75 by the lever 171 and the link 176 (Figs. 1, 8 and 9). The operation of this mechanism has been described in detail above, the blank holder being advanced a proper distance at 80 the end of each cycle.

I will now briefly describe the operation of the machine when a "leader" is in printing position and a "follower" is positioned to be fed into the printing position after the second impression has been made of the "leader." The position which the "follower" occupies while the impressions are being taken of the "leader" may be termed the "determining" position as a printing device in this position determines the subsequent behavior of the mechanism which controls the numbering machine. When a "follower" is in the "control" position, its tab 102 is adapted to depress the determining finger 287 which in turn depresses the rod 286, as best illustrated in Fig. 18. Referring, however, to Fig. 17 and assuming that a "leader" is in the printing position and a follower is in the "determining" position, and that a first impression of the "leader" is to be made, 90 it is apparent that when the rod 286 is depressed it angularly displaces the shaft 270 and causes the latch 281 to be moved to the left (Fig. 17). The shoulder 282 of the latch does not immediately engage the lug 277 of the bell crank lever 267 as the lever follows 95 the latch by reason of the spring 278. The operation of the remaining mechanism during the first impression cycle is substantially that of the first impression cycle when a 100 "leader" is in the "determining" position, but at the end of this cycle the anti-friction roller 122 engages the arm 268 of the bell crank lever 267 and brings it into a position 105 wherein the latch 281 engages the lug 277 of the bell crank lever 267 so that on the down-stroke of the platen arm at the beginning of the second impression the roller 265 is stopped in an intermediate position, 110 as shown in Fig. 18. Then when the push rod 115 advances, it fulcrums on the roller 265 and its shoulder 338 passes above the shoulder 337 on the accumulator bar 332. But the numbering machine is lowered as the dog 296 engages the shoulder 309 of the lever 310 and angularly displaces the lever in a counter clock-wise direction (Fig. 19) 115 so that it in turn angularly displaces the lever 312 in a clock-wise direction (Fig. 19) to bring the cam 317 into a position wherein 120 125 130

it allows the numbering machine to drop out of its printing position. The lever 312 is locked in its displaced position by means of the latch 325 as clearly illustrated in Fig. 19. If a "leader" is brought into the "determining" position during the up-stroke of the platen, the remaining parts of the machine will be restored to their normal positions, and after two impressions have been made of the "follower" in the printing position the roller 331 on the accumulator bar 332 will disengage the latch 325 from the lever 312 so that the lever may be restored to its normal position by means of the spring 339. At the same time the roller 293^a on the push rod 115 will angularly displace the bell crank lever 291 to trip the latch 281, thus permitting the bell crank lever 267 and the lever 273 to return to their normal positions relative to each other.

The printing machine will operate continuously until the last printing device (in practice a blank) has been withdrawn from the magazine unless the operator brings the machine to a stop by means of the lever 257, or unless the bent plate 162 engages the stop lever 163.

While the printing machine operates through two cycles each time a "leader" or a "follower" is in the printing position (divided printing), no impression will actually be taken during the second cycle when a "follower" is in that position as the "followers" do not carry type plates 99.

I will now describe the operation of the printing machine when it has been adjusted for "consecutive printing" so that each printing device will be presented to the platen roller a single time, and so that the names of the holders of title and the descriptions of the various parcels of land will fall in a single column as shown in Fig. 27. The identifying numbers are printed whenever a "leader" appears in the printing position.

To adjust the printing machine for "consecutive printing" it is necessary to bring the pin 211 of the eccentric pin 210 against the stop pin 213 (Fig. 8) so that the disk 86 may remain in the position wherein it is shown in Fig. 15, the bifurcated plate 76 being reversed, as shown in Fig. 25. The push rod 142 is moved inwardly until its pin 145 rests in the notch 144 of the bracket 139 and the bent rod 129 is positioned to engage one of the deeper notches 140 of the ratchet wheel 131. From the above detailed description of these parts of the machine and their associated mechanisms, it is of course understood that each printing device will be presented but a single time to the platen roller.

When the disk 86 is in the position wherein it is shown in Fig. 15, the blank holder 65 will be in the position indicated in dotted

lines in Fig. 1. The gauge bar 261^a must then be placed in its left-hand position which is shown in dotted lines in the same figure. The mask 215 is positioned in the manner hereinbefore described. The blank holder 70 is replaced by one having properly spaced teeth 153 and the pin 173 is positioned in the aperture 173^b or the aperture 173^c of the lever 171 to change the effective stroke of the left hand end of the lever 75 (Fig. 1). Which aperture is to be used is determined by the spacing of the teeth 153. The pin 172 is moved into the aperture 170^a in the pawl 170. The eccentric pin 307 is turned to the position shown in Fig. 20, 80 and the link 342 is disengaged from the pin 331^a.

After a supply of printing devices has been placed in the magazine and a blank has been correctly positioned in the machine 85 the operator depresses the foot treadle (not shown) and sets the machine in operation.

Assuming that a "leader" has been brought to the printing position and that a second "leader" is in "determining" position, 90 the push rod 115 advances during the down-stroke of the platen arm 46 and its shoulder 338 engages the shoulder 337 on the accumulator bar to displace the accumulator bar. This insures that the accumulating mechanism 95 of the numbering machine will be actuated during the up-stroke of the platen arm. Then if at the end of the cycle of operations a third "leader" has been brought into the determining position, the mechanism 100 of the printing machine will be restored to the condition which obtained at the beginning of the cycle with the exception that the blank has been advanced and the numbering machine has been adjusted to 105 print the next identifying number. The machine continues to operate in this manner until a follower is brought into the "determining" position whereupon the rod 286 will be depressed as shown in Fig. 21. During 110

the following stroke of the platen arm 46, the roller 265 assumes a position which is identical with the position it assumes when a like condition obtains in "divided" printing and the push rod 115 on its forward stroke fulcrums on the roller so that its shoulder 338 passes over the shoulder 337 on the accumulator bar 332. This movement of the push rod 115 is illustrated by dotted lines in Fig. 22. It follows, of course, that the accumulating mechanism of the numbering machine will not be actuated during the return stroke of the push rod. However, during this return stroke of the push rod 115 the dog 295 angularly displaces the lever 312 120 into the position wherein it is shown in Fig. 23 and the latch 342 locks it in that position. The cam 317 then presents its flattened surface 319 to the numbering machine 125 which immediately drops out of its 130

printing position so that no identifying number will be given to the impression taken from the "follower" during the following cycle of operations. When a "leader" finally appears in the "determining" position, the latch 325 is disengaged from the lever 312 in the identical manner it is disengaged therefrom when a like condition obtains in "divided" printing. The lever 312 is then 10 returned to its normal position by the spring 339.

I am aware that changes in the form, construction and arrangement of parts may be made without departing from the spirit and 15 without sacrificing the advantages of the invention and I reserve the right to make all such changes as fairly fall within the scope of the following claims.

I claim:—

20 1. In a printing machine, a platen, a plurality of printing devices, means for presenting each printing device to a printing position relative to the platen, means for causing said platen to make impressions from 25 said printing devices upon a blank, blank holding mechanism, means for automatically advancing the blank holding mechanism, and means for shifting the blank holding mechanism at an angle to the direction it is advanced to space the impressions made upon 30 the blank.

2. In a printing machine, a platen, a plurality of printing devices, means for presenting each printing device to a printing position relative to the platen, means for causing said platen to make impressions from 35 said printing devices upon a blank, blank holding mechanism, means for automatically advancing the blank holding mechanism, and means for reciprocating the blank holding mechanism at an angle to the direction it is advanced to space the impressions made upon the blank.

3. In a printing machine, a platen, a plurality of printing devices, means for presenting each printing device to a printing position relative to the platen, means for taking impressions from the printing devices upon a blank, means for automatically advancing 45 the blank through the machine, and means for shifting the blank laterally to space the impressions made thereon.

4. In a printing machine, a platen, a plurality of printing devices, means for presenting each printing device to a printing position relative to the platen, means for taking impressions from the printing devices upon a blank, means for automatically advancing the blank through the machine, and means 55 for reciprocating the blank laterally to space the impressions thereon.

5. In a printing machine, a shaft, means for continuously driving the shaft, a plurality of printing devices, means actuated 60 by the shaft for taking impressions from the

printing devices upon a blank, means operated by the shaft for advancing the blank in the machine, said last mentioned means being adapted to be operated a plurality of times without manual actuation thereof, and 70 means for shifting the blank at an angle to the direction in which it is advanced to space the impressions made thereon.

6. In a printing machine, a shaft, means for continuously driving the shaft, a plurality of printing devices, means actuated by 75 the shaft for taking impressions from the printing devices upon a blank, means operated by the shaft for advancing the blank in the machine, said last mentioned means being 80 adapted to be operated a plurality of times without manual actuation thereof, and means for reciprocating the blank at an angle to the direction in which it is advanced to space the impressions made thereon. 85

7. In a printing machine, a platen, a plurality of printing devices, means for presenting each printing device to printing position in respect to the platen, means for taking an impression from said printing device on a 90 blank, means for automatically imparting a step-by-step movement in one direction to a blank, and means for shifting the blank in a direction normal to the direction of the step-by-step movement to space the impressions 95 made upon the blank.

8. In a printing machine, a platen, a plurality of printing devices, means for presenting each printing device to printing position in respect to the platen a plurality of times, 100 means for taking an impression from said printing device on a blank, blank holding mechanism, means for automatically imparting a step-by-step movement to the blank holding mechanism, and means for shifting the blank holding mechanism in a direction 105 normal to the direction of the step-by-step movement to space the impressions made upon the blank.

9. In a printing machine, a platen, a plurality of printing devices, means for presenting each printing device to printing position in respect to the platen a plurality of times, means for adjusting the last mentioned means to present each printing device to printing position in respect to the platen a single time, means for taking an impression from said printing device on a blank, blank holding mechanism, and means for reciprocating the blank holding mechanism to space 115 the impressions made upon the blank. 110

10. In a printing machine, a platen, a plurality of printing devices, means for presenting each printing device to printing position in respect to the platen a plurality of times, 120 means for adjusting the last mentioned means to present each printing device to printing position in respect to the platen a single time, means for taking an impression from said printing device on a blank, blank holding mechanism, and means for reciprocating the blank holding mechanism to space 125 the impressions made upon the blank. 115

lateral direction after the presentation of a printing device to the platen.

22. In a printing machine, a plurality of printing devices, means for taking a consecutive series of impressions from the printing devices upon a blank, a numbering machine, and means controlled by the printing devices for causing the numbering machine to number some of the impressions and for preventing the numbering machine from numbering others of the impressions.

23. In a printing machine, a platen, a plurality of printing devices, means for presenting each printing device to the platen, blank holding mechanism, means for advancing the blank holding mechanism, means for reciprocating the blank holding mechanism in a direction normal to the direction in which it is advanced, a numbering machine, and means controlled by the printing devices for controlling the numbering machine.

24. In a printing machine, a platen, a plurality of printing devices, means for presenting each printing device to the platen a plurality of times, means for adjusting the last-mentioned means to present each printing device to the platen a single time, blank holding mechanism, means for reciprocating the blank holding mechanism in a direction normal to the direction in which it is advanced, a numbering machine, and means controlled by the printing devices for controlling the numbering machine.

25. 25. In a printing machine, a platen, a plurality of printing devices, means for presenting each printing device to the platen, blank feeding mechanism, a numbering machine, and means controlled by the printing devices for bringing the numbering machine into and out of a printing position.

26. In a printing machine, a platen, a plurality of printing devices, means for presenting each printing device to the platen, blank holding mechanism, means for advancing the blank holding mechanism, means for reciprocating the blank holding mechanism in a direction normal to the direction in which it is advanced, a numbering machine, and means controlled by the printing devices for bringing the numbering machine into and out of a printing position.

27. In a printing machine, a platen, a plurality of printing devices, means for presenting each printing device to the platen a plurality of times, means for adjusting the last-mentioned means to present each printing device to the platen a single time, blank holding mechanism, means for reciprocating the blank holding mechanism in a direction normal to the direction in which it is advanced, a numbering machine, and means controlled by the printing devices for bringing the numbering machine into and out of a printing position.

28. In a printing machine, a platen, a plurality of printing devices, means for presenting each printing device to the platen, blank holding mechanism, means for advancing the blank holding mechanism, means for reciprocating the blank holding mechanism in a direction normal to the direction in which it is advanced, a numbering machine having accumulating mechanism, and means controlled by the printing devices for actuating the accumulating mechanism.

29. In a printing machine, a platen, a plurality of printing devices, means for presenting each printing device to the platen a plurality of times, means for adjusting the last-mentioned means to present each printing device to the platen a single time, blank holding mechanism, means for reciprocating the blank holding mechanism in a direction normal to the direction in which it is advanced, a numbering machine having accumulating mechanism, and means controlled by the printing devices for actuating the accumulating mechanism.

30. In a printing machine, a platen, a plurality of printing devices, means for presenting each printing device to the platen, blank feeding mechanism, a numbering machine, means for bringing the numbering machine into and out of a printing position, and means controlled by the printing devices for locking the numbering machine out of the printing position.

31. In a printing machine, a platen, a plurality of printing devices, means for presenting each printing device to the platen, blank holding mechanism, means for advancing the blank holding mechanism, means for reciprocating the blank holding mechanism in a direction normal to the direction in which it is advanced, a numbering machine, means for bringing the numbering machine into and out of a printing position, and means controlled by the printing devices for locking the numbering machine out of the printing position.

32. In a printing machine, a platen, a plurality of printing devices, means for presenting each printing device to printing position in respect to the platen a plurality of times, means for taking an impression from said printing device on a blank, blank feeding mechanism, operating automatically to advance the blank in the machine, and means for shifting the blank to place separate impressions of each printing device in separate columns on the blank.

33. In a printing machine, a platen, a plurality of printing devices, means for presenting each printing device to printing position in respect to the platen a plurality of times, blank holding mechanism, operating automatically to advance the blank in the machine, means for taking an impression

from said printing device on a blank, and means for causing the platen to make an impression of one portion of a printing device in one column on the blank and to make an impression of a different portion of the printing device in another column on the blank.

34. In a printing machine, a platen, a plurality of printing devices, means for presenting each printing device to printing position in respect to the platen a plurality of times, means for taking an impression from said printing device on a blank, blank feeding mechanism operating automatically to advance the blank in the machine, blank shifting mechanism, a mask, and means for bringing the mask into and out of a position wherein it covers a portion of a printing device presented to the platen during a printing operation.

35. In a printing machine, a platen, a plurality of printing devices, means for presenting each printing device to printing position in respect to the platen a plurality of times, means for taking an impression from said printing device on a blank, blank holding mechanism, means for advancing the blank holding mechanism in a step-by-step manner across the printing machine, means for reciprocating the blank holding mechanism to space the impressions made upon the blank, a mask, and means for bringing the mask into and out of a position wherein it covers a portion of a printing device presented to the platen during a printing operation.

36. In a printing machine, a platen arm, a platen slidably journaled with respect to the platen arm, a cam slidably journaled with respect to the platen arm and adapted to guide the platen, and means for reciprocating the cam.

37. In a printing machine, a platen arm, a platen slidably journaled with respect to the platen, a cam slidably journaled with respect to the platen arm and adapted to guide the platen, means for reciprocating the cam, a plurality of printing devices, means for presenting each printing device to the platen a plurality of times, and means operatively connecting the last-mentioned means with the means for reciprocating the cam.

38. In a printing machine, a platen arm, a platen, a cam carried by the platen arm for controlling the platen, a plurality of printing devices, means for presenting each printing device to the platen, and means operatively connecting the last-mentioned means with the cam.

39. In a printing machine, a platen arm, a platen, a cam carried by the platen arm for controlling the platen, a plurality of printing devices, means for presenting each printing device to the platen, means oper-

atively connecting the last-mentioned means with the cam, a mask, and means for bringing the mask into and out of a position wherein it covers a portion of a printing device presented to the platen.

40. In a printing machine, a platen arm, a platen slidably journaled with respect to the platen arm, a cam carried by the platen arm for controlling the platen, means for bringing the cam into a plurality of positions with respect to the platen arm, a plurality of printing devices, means for presenting each printing device to the platen, blank holding mechanism, and means for reciprocating the blank holding mechanism to space impressions made upon the blank.

41. In a printing machine, a platen, a plurality of printing devices, means for presenting each printing device to printing position in respect to the platen, means for taking an impression from said printing device on a blank, means for advancing a blank to printing position, and means for reciprocating the blank in respect to the platen and printing device to space the impressions made therein.

42. In a printing machine, a platen, a plurality of printing devices, means for presenting each printing device to printing position in respect to the platen, means for taking an impression from said printing device on a blank, means for imparting a step by step movement to a blank to bring it to printing position in respect to said platen and printing device and means for shifting the blank in a direction normal to the direction of the step by step movement and relative to the platen and printing device to space the impressions made thereon.

43. In a printing machine, a platen, a plurality of printing devices, means for presenting each printing device to printing position in respect to the platen, means for taking an impression from said printing device on a blank, means for imparting a step by step movement to a blank to bring it to printing position and means for reciprocating the blank in a direction normal to the direction of the step by step movement and relative to the platen and printing device to space the impression made thereon.

44. In a printing machine, means for imparting a step-by-step movement to a blank to bring it to a printing position, means for reciprocating the blank in a direction normal to the direction of the step-by-step movement, a numbering machine, and means operatively connecting a numbering machine with the first-mentioned means.

45. In a printing machine, means for bringing a blank to a printing position, means for reciprocating the blank in a direction normal to the direction in which it is fed, a numbering machine, and means operatively connected with the first-men-

tioned means for bringing the numbering machine into and out of a printing position.

46. In a printing machine, means for feeding a blank to a printing position, means for reciprocating a blank in a direction normal to the direction in which it is fed, a numbering machine having accumulating mechanism, and means operatively connected to the first mentioned means for actuating

10 the accumulating mechanism.

47. In a printing machine, means for imparting a step-by-step movement to a blank to bring it to a printing position, means for shifting the blank in a direction normal

15 to the direction of the step-by-step movement, a numbering machine having accumulating mechanism, and means operatively connected with the first-mentioned means for bringing the numbering machine into and 20 out of a printing position and for actuating the accumulating mechanism.

48. In a printing machine, a platen, means for imparting a step-by-step movement to a blank to present the blank to the platen 25 a plurality of times, means for reciprocating the blank, means cooperating with the platen to print on said blank, a mask, and means for reciprocating the mask to expose different portions of said blank.

49. In a printing machine, a platen arm, a platen carried by the platen arm, a cam for guiding the platen, the cam being carried by the platen arm, means for imparting a step-by-step movement to a blank to present it to the platen a plurality of times, means for reciprocating the blank, a mask co-operating with the cam, and means operatively connecting the mask and the cam to the means for reciprocating the blank.

50. In a printing machine, a platen, a plurality of printing devices, means for presenting each printing device to the platen, a numbering machine including accumulating mechanism, means including a push rod 45 for actuating the accumulating mechanism, and means controlled by the printing devices for controlling the push rod.

51. In a printing machine, a platen, a plurality of printing devices, means for presenting each printing device to the platen, a numbering machine including accumulating mechanism, means including a push rod for actuating the accumulating mechanism, means controlled by the printing devices for 50 controlling the push rod, and means carried by the push rod for bringing the numbering machine out of its printing position.

52. In a printing machine, a platen, a plurality of printing devices, means for presenting each printing device to the platen, a numbering machine including accumulating mechanism, a lever, a link connecting one end of the lever with the accumulating mechanism, means for angularly displacing 60 the lever to actuate the accumulating mech-

anism, and means controlled by the printing devices for controlling the last-mentioned means.

53. In a printing machine, a platen, a plurality of printing devices, means for presenting each printing device to the platen, a numbering machine including accumulating mechanism, a lever pivotally mounted intermediate its ends, a link connecting one end of the lever with the accumulating mechanism, a push rod normally registering with the other end of the lever, means for reciprocating the push rod, and means controlled by the printing devices for controlling the last-mentioned means. 75

54. In a printing machine, a platen, a plurality of printing devices, means for presenting each printing device to the platen, a numbering machine including accumulating mechanism, a lever pivotally mounted intermediate its ends, a link connecting one end of the lever with the accumulating mechanism, a push rod normally registering with the other end of the lever, means for reciprocating the push rod, means controlled 80 by the printing devices for controlling the last-mentioned means, and means carried by the push rod for bringing the numbering machine out of its printing position. 85

55. In a printing machine, a platen, a plurality of printing devices, means for presenting each printing device to the platen, a numbering machine including accumulating mechanism, a lever pivotally mounted intermediate its ends, a link connecting one end of the lever with the accumulating mechanism, a push rod normally positioned to engage the other end of the lever, means for reciprocating the push rod, means controlled 90 by the printing devices for controlling the last-mentioned means, means carried by the push rod for bringing the numbering machine out of 95 its printing position. 100

56. In a printing machine, a platen, a plurality of printing devices, means for presenting each printing device to the platen a plurality of times, means for adjusting the last-mentioned means to present each printing device to the platen a single time, a numbering machine including accumulating mechanism, means including a push rod for actuating the accumulating mechanism, and means controlled by the printing devices for 115 controlling the last-mentioned means. 120

57. In a printing machine, a platen, a plurality of printing devices, means for presenting each printing device to the platen a plurality of times, means for adjusting the last-mentioned means to present each printing device to the platen a single time, a numbering machine including accumulating mechanism, a lever operatively connected to 125 the accumulating mechanism, a push rod 130

normally positioned to engage the lever, means for reciprocating the push rod, and means controlled by the printing devices for bringing the push rod into a position where-
5 in its cannot engage the lever.

58. In a printing machine, a platen, a plurality of printing devices, means for presenting each printing device to the platen, a numbering machine including accumulat-
10 ing mechanism, a lever pivotally mounted intermediate its ends, a link connecting one end of the lever with the accumulating mechanism, a push rod normally positioned to engage the other end of the lever, means for reciprocating the push rod, means controlled by the printing devices for controlling the last-mentioned means, means carried by the push rod for bringing the numbering machine out of its printing position, means for
15 locking the numbering machine out of its printing position, and means carried by the lever for unlocking the numbering machine.

59. In a printing machine, a platen arm, a platen, a plurality of printing devices, means for presenting each printing device to the platen, blank holding mechanism, and means for reciprocating the blank holding mechanism and comprising a segmental gear operatively connected to the platen arm, a second segmental gear meshing with the first-mentioned segmental gear, and means connecting the second segmental gear with the blank holding mechanism.

60. In a printing machine, a platen arm, a platen, a plurality of printing devices, means for presenting each printing device to the platen, means for imparting a step-by-step movement to a blank to present it to the platen a plurality of times, and means for shifting the blank in a direction normal to the direction of the step-by-step movement and comprising a segmental gear operatively connected to the platen arm, and a second segmental gear meshing with the first-mentioned segmental gear.

61. In a printing machine, a platen arm, a platen, a plurality of printing devices, means for presenting each printing device to the platen, means for feeding a blank to the platen, and means for shifting the blank in a direction normal to the direction in which it is fed and comprising a segmental gear operatively connected to the platen arm, a second segmental gear meshing with the first-mentioned segmental gear, a ratchet, and a pawl movable with the second segmental gear and co-operating with the ratchet.

62. In a printing machine, a platen arm, a platen, a plurality of printing devices, means for presenting each printing device to the platen, a blank holder, means for imparting a step-by-step movement to the blank holder to present the blank to the platen a plurality of times, and means for shifting

the blank in a direction normal to the direction of the step-by-step movement and comprising an oscillatory member, and means actuated by the oscillatory member operatively connected to the blank holder. 70

63. In a printing machine, a platen arm, a platen carried by the platen arm, a cam for guiding the platen, the cam being carried by the platen arm, a lever pivotally mounted on the platen arm and operatively connected to the cam, and means for angularly displacing the lever to shift the cam. 75

64. In a printing machine, a platen arm, means for oscillating the platen arm, a platen carried by the platen arm, a cam for guiding the platen, the cam being carried by the platen arm, a lever pivotally mounted on the platen arm and operatively connected to the cam, means for angularly displacing the lever to shift the cam, and means actuated by the movements of the platen arm for controlling the last-mentioned means. 80

65. In a printing machine, a platen arm, means for oscillating the platen arm, a platen carried by the platen arm, a cam 85 slidably journaled on the platen arm for guiding the cam, a lever pivotally mounted on the platen arm and operatively connected to the cam, means movable into a plurality of positions for displacing the lever to shift the cam, and means actuated by the movements of the platen arm for controlling the last mentioned means. 90

66. In a printing machine, a platen arm, means for oscillating the platen arm, a platen carried by the platen arm, a cam slidably journaled on the platen arm to guide the platen, a lever pivotally mounted on the platen arm and operatively connected to the cam, and reversible means for angularly displacing the lever to shift the cam. 100

67. In a printing machine, a platen, a plurality of printing devices, means for presenting each printing device to printing position in respect to the platen, means for 110 taking an impression from said printing device on a blank, a detachable blank holder, means for slidably journaling the blank holder, means for imparting a step by step movement to the blank holder and means for 115 reciprocating the means for slidably journaling the blank holder.

68. In a printing machine, a driving shaft, a driven shaft, means including a clutch operatively connecting the driving shaft with 120 the driven shaft, a blank holder, means for imparting a step by step movement to the blank holder, means for shifting the blank holder in a direction normal to the direction of the step by step movement, and means 125 actuated by the blank holder for controlling the clutch.

69. In a printing machine, a driving shaft, a driven shaft, means including a clutch operatively connecting the driving shaft to 130

the driven shaft, means for imparting a step-by-step movement to the blank to be printed, and means for rendering the clutch functionally inoperative when the blank is advanced to a predetermined position in the machine.

70. In a printing machine, a driving shaft, a driven shaft, means including a clutch operatively connecting the driving shaft to the driven shaft, means for imparting a step-by-step movement to the blank to be printed, means for shifting the blank in a direction at an angle to the direction of the step-by-step movement, and means for rendering the clutch functionally inoperative when the blank is advanced to a predetermined position in the machine.

71. In a printing machine, means for holding a sheet of paper entirely flat in the machine, a plurality of printing devices, means for advancing the sheet, means for shifting the sheet laterally, and means for taking impressions of the printing devices upon the sheet.

72. In a printing machine, means for holding a sheet of paper entirely flat in the machine, a plurality of printing devices, means for advancing the sheet, means for shifting the sheet laterally, means for taking impressions of the printing devices upon the sheet, means for actuating the advancing means, and means for rendering the actuating means functionally inoperative when the sheet reaches a predetermined position.

73. In a printing machine, means for holding a sheet of paper flat, a plurality of printing devices, means for advancing the sheet step-by-step, means for taking impressions upon the sheet from the printing devices, and means for causing relative motion between the impression taking means and the sheet to space the impression laterally of the sheet.

74. In a printing machine, a plurality of printing devices, a magazine for holding

the printing devices, means for feeding the printing devices from the magazine one at a time, means for advancing a blank step-by-step, means for taking impressions upon the blank from the printing devices, means for shifting the blank laterally to space the impressions thereon, and means for rendering said advancing means functionally inoperative after it has advanced the blank to a predetermined position.

75. In a printing machine, a plurality of printing devices, a magazine for holding the printing devices, means for feeding the printing devices from the magazine one at a time, means for advancing a blank longitudinally and step-by-step, means for taking impressions upon the blank from the feeding devices, and means for rendering said advancing means functionally inoperative after it has advanced the blank to a predetermined position.

76. In a printing machine, a platen, a plurality of printing devices, two spaced magazines for holding the printing devices, common means for advancing each printing device from one magazine to the other and for presenting each printing device to a printing position relative to the platen, means for actuating said platen to take an impression of each printing device upon a blank, blank holding mechanism, and means for reciprocating the blank holding mechanism to space the impressions on the blank.

77. In a printing machine, a plurality of printing devices, a plurality of spaced magazines, means for holding a blank substantially flat between the magazines, means for advancing the blank holding mechanism, means for advancing the printing devices from one magazine to another, and means for taking impressions from said printing devices upon the blank while they are advancing from one magazine to another.

JOSEPH S. DUNCAN.
